BEAM STRUCTURE

Earl J. W. Ragsdale, Norristown, and Albert G. Dean, Narberth, Pa., assignors to Edward G. Budd Manufacturing Company, Philadelphia, Pa., a corporation of Pennsylvania

Original application April 27, 1932, Serial No. 607,690. Divided and this application April 13, 1936, Serial No. 74,135

5 Claims. (Cl. 189—37)

This invention relates to improvements in structural members and more particularly to an improved beam or girder which is particularly adapted to be fabricated from thin, light gauge sheet metal strips suitably formed into the desired cross section. It is more particularly a division of our co-pending application, Serial Number 607,690 filed April 27, 1932 for Rail car body.

One of the principal objects of this invention is to provide an improved beam, girder, column or the like having a decreased quantity and therefore weight of metal, in which the cost of the structure can be greatly reduced, and one in which the manufacture and assembly is especially facilitated as by adapting the respective parts to spot welding.

A further object of the invention is to provide an improved sheet metal beam, girder, column or the like which has a maximum strength considering the amount and kind of material employed, and one which is highly effective in operation and readily adaptable for cooperation with appurtenant parts.

A further and more specific object of the invention is to provide an improved box beam consisting of angular cross section chord members and web members which are vertically stiffened longitudinally of the beam, such beam being closed to form a box-like structure and in which all of the parts are relatively narrow sheet metal strips preferably of a high tensile stainless steel spot welded together.

Further objects and advantages of the invention will appear from the following description of a preferred form of embodiment thereof taken in connection with the attached drawing, in which:

Fig. 1 is a perspective view of the beam in accordance with the invention.

40 Fig. 2 is a side elevation of a part of the beam shown in Fig. 1.

Fig. 3 is a horizontal section taken substantially along the line 3—3 of Fig. 2.

The preferred form of embodiment of our invention is generally represented by beam 10 of truss type having upper and lower chord members 11 and 12, intermediate and bodily spaced plate webs 14, cover plates 16, and longitudinally spaced, vertically extending stiffeners 18. Each of these parts is conveniently made from sheet metal strips of relatively narrow gauge and formed into the desired cross sections as by well known machinery, the formed pieces being subsequently spot welded for extreme lightness with maximum strength. If desired, stainless alloy steels may

be used and further economies can be obtained in ease of fabrication and in eliminating corrosion factors.

In the preferred construction, each chord member 11 or 12 is preferably of angular cross section having a flange, as 11a for example, running along the length of the web and secured to it as by spot welding. Another flange 11b extends laterally outward from the edge of the web and gives the structure a lateral stiffness while cooperating with the first flange to make a longitudinally extending angle at the edge of the web. This laterally extending flange 11b also serves as a support for the cover plates 16 which form the chord members into closed box sections.

In this construction, each set of longitudinally extending angles is part of the same chord member, being joined through internally extending flange 11c having longitudinally extending bead 11d, but this is principally because of the ease of forming a channel shaped member with outwardly projecting flanges. From a structural standpoint however, the longitudinally extending angles at the sides of the webs are the principal elements of the chords, the internal flange or channel bottom serving to space the web plates 14, and giving some additional stiffness.

The truss web plates may be relatively thin gauge stock as compared with the gauge of the chord members 11 and 12, although considerable variation is possible as all of the beam elements are formed from separate strips. These web plates are divided by diagonal indentations 15 into a plurality of rectangular portions, which portions are prevented from "dishpanning" 35 through the stiffened indentations.

These rectangular portions are further defined by channel shape reenforcing vertical truss members 18 extending from chord flange to chord flange and presented outwardly of the beam and welded by their bottoms to the web plates 14. The bottoms of these strut members may be stiffened and rendered more rigid by the offset 19. It is of course to be understood that the webs might be stiffened by angles or be of other shapes 45 to support transverse loads. The channels 18 are welded in place prior to the welding of the webbing to the chord members 11 and 12, and accessibility for welding of all parts is attained thereby.

The cover plates 16 are conveniently secured to the outwardly projecting flanges of the chord members as by spot welding, such operation preferably taking place after the web plates are secured to the chord member flanges. These plates 16 may be flat or of centrally depressed

section, forming a channel which cooperates with the chord member flanges to maintain the spacing of the webs. If desired, the outer edge of the plates 16 may be formed into flanges at 5 right angles to the main plane of the plates to facilitate attachment of other structural elements.

In this construction, the truss elements can readily be arranged to take the predetermined 10 loads to be applied to the beam in a most efficient manner and it will be apparent that various elements may be of different thickness without interfering with the ready fabrication of the beam. Furthermore, all of the elements are 15 initially of such open section that the parts may be effectively welded each to the other in a continuously operating welding machine, if so desired. The beam is symmetrical with respect to a vertical longitudinal plane and each chord, 20 as well as the entire beam, is of box shape having great rigidity and resistance to bending. Such a beam thus has a general application.

While we have described a preferred form of embodiment of the invention, it is obvious that 25 other modifications may be made thereto and it is therefore our aim to cover broadly the disclosure herein and as more particularly set forth in the claims appended hereinafter.

What we claim is:

30 1. A beam comprising a pair of bodily spaced webs, a one-piece angular chord member having flanges extending along the edges of said webs and being secured to the edge portions of the respective webs, other flanges extending laterally 35 outwardly of said webs, and a bridging chord member of channel section fitted between portions of the angular chord member and across the edges of the webs and having flanges overlapping flanges of the angular chord member and secured thereto, the channel section of the bridging chord member spacing the webs apart through engagement of the side walls of the channel cross section with the chord member.

2. A beam comprising a pair of spaced sheet 45 metal web members, a chord structure spacing and joining adjacent ends of said web members, said chord structure including substantially right angular side portions each having one flange overlapping and secured to the adjacent 50 web member, one flange extending inwardly and another flange extending laterally outwardly from said first named flange, and a closing strip having shoulders abutting and spacing the 55 angular chord side portions and overlapping said

laterally extending flange of the angular side portions and secured thereto.

3. A beam comprising a pair of spaced sheet metal web members, a chord structure spacing and joining adjacent ends of said web members, said chord structure including substantially right angular side portions each having one flange overlapping and secured to the adjacent web member and another flange extending laterally outwardly from said first named flange, 10 and a closing strip having shoulders abutting and spacing the angular chord side portions and overlapping said laterally extending flange of the angular side portions and secured thereto, the flanges of the chord side portions overlapping 15 the web members being transversely interconnected at their inner margins and being integral with respect to each other.

4. A beam comprising a top chord structure, a bottom chord structure, and a web structure, said 20 web structure including spaced metallic sheets, transversely extending longitudinally spaced web reinforcing means having outwardly projecting flange portions, said web structure extending between and being secured to the respective chord 25 structures, one of said chord structures including a side chord member extending along the edge of each web sheet and having a portion extending in the direction of the body of the web sheet and overlapping the same and secured thereto in said 30 region of overlap, an outwardly extending portion beyond the edges of the web sheet and an inwardly extending web stabilizing flange extending from said web overlapping portion, and a through-running bridging chord member secured to the side chord members and spacing 35 the web sides.

5. A closed box section beam of the class described comprising chord members and web members, said web members being spaced by said 40 chord members, said web members being secured adjacent their ends to portions of the respective chord members, said chord members having other portions overhanging said web members and longitudinally extending bridging members 45 secured to the overhanging portions of said chord members in the overhanging region, and having shoulders to additionally aid in spacing said web members and to close the space between said 50 web members, said chord members being of deep, internally closed channel shape, constituting, with the bridging members, closed box section chords.

EARL J. W. RAGSDALE,
ALBERT G. DEAN.
